DESIGN FOR A LATHE OR SIMILAR ARTICLE

Carroll E. Miller, Windsor, Vt., assignor to Cone
Automatic Machine Company, Inc., Windsor,
Vt., a corporation of Vermont

Application June 19, 1939, Serial No. 85,560

Term of patent 14 years

To all whom it may concern:

Be it known that I, Carroll E. Miller, a citizen
of the United States, residing at Windsor, in
the county of Windsor and State of Vermont,
have invented a new, original, and ornamental
Design for a Lathe or Similar Article, of which
the following is a specification, reference being
had to the accompanying drawings, forming part
thereof.

Figure 1 is a perspective view and
Figures 2 and 3 are left end elevation and top
plan views, respectively, of a lathe or similar ar-
ticle, showing my new design.

I claim:

The ornamental design for a lathe or similar
article, as shown.

CARROLL E. MILLER.
